US0D1061124S

(12) **United States Design Patent** (10) **Patent No.:** **US D1,061,124 S**
(45) **Date of Patent:** **** Feb. 11, 2025**

(54) **AIR FRYER**

(71) Applicant: **Guangdong Midea Consumer Electric Manufacturing Co., Ltd.**, Foshan (CN)

(72) Inventors: **Bingcan Liang**, Guangdong (CN);
Yingwen Huang, Guangdong (CN)

(73) Assignee: **Guangdong Midea Consumer Electric Manufacturing Co., Ltd.**, Foshan (CN)

(**) Term: **15 Years**

(21) Appl. No.: **35/519,373**

(22) Filed: **Aug. 23, 2023**

(80) **Hague Agreement Data**

Int. Filing Date: **Aug. 23, 2023**

Int. Reg. No.: **DM/233639**

Int. Reg. Date: **Aug. 23, 2023**

Int. Reg. Pub. Date: **Dec. 15, 2023**
